UNITED STATES PATENT OFFICE.

JOHN S. BRENNAN, OF MILWAUKEE, WISCONSIN.

THERMOSTATICALLY-CONTROLLED RADIATOR-VALVE.

1,219,699.

Specification of Letters Patent. Patented Mar. 20, 1917.

Application filed January 22, 1916. Serial No. 73,547.

To all whom it may concern:

Be it known that I, JOHN S. BRENNAN, a citizen of the United States, and resident of Milwaukee, in the county of Milwaukee 5 and State of Wisconsin, have invented certain new and useful Improvements in Thermostatically Controlled Radiator-Valves; and I do hereby declare that the following is a full, clear, and exact description thereof.

10 The present invention relates to new and useful improvements in trap valves and is more particularly related to the provision of an automatic valve for relieving air and steam from the radiators of various types

15 of steam heating systems.

It is in general the object of the present invention to improve the structure and render more positive the operation of valves of this character. In the latter connection, a 20 disadvantage encountered in present types of radiator trap valves including a thermostat formed of flexible members and a volatile fluid, is that a positive retraction of the valve head upon lowering of tempera- 25 ture is not had sufficiently to free the mouth of the valve and it is therefore more specifically an object to provide an independent means for retracting the valve head upon lowering of the temperature to thus relieve 30 the thermostat member from the work of such retraction.

Another object resides in the provision of a thermostatically controlled valve head structure wherein the valve head is posi- 35 tively guided for proper movement with relation to its seat.

Another object resides in the provision of an adjusting means with respect to the valve and its seat whereby the structure may be 40 adjusted for operation under various differ- 50 ing conditions.

A further object resides in the provision of an improved thermostat structure in connection with the valve head and its guide 45 whereby a simple and ready assembly of the thermostat structure is provided for and whereby a maximum flexibility of the thermostat may be had.

A still further object resides in the pro- 50 vision of a thermostatically controlled valve associated with a radiator in such manner that a maximum sensitiveness of the thermo- 55 stat element is provided for, and to this end a structure is contemplated wherein the steam does not surround the valve head and thermostat in normal closing position, but

supplies its head indirectly to the thermo- 60 stat.

With the above and other objects and ad- 65 vantages in view, the invention resides more particularly in the novel combination, for- 70 mation and arrangement of parts more fully hereinafter described and particularly point- 75 ed out in the appended claims.

In the drawings:

Figure 1 is a vertical sectional view taken centrally through a preferred form of radi- 70 ator trap valve embodying the present in- 75 vention, and showing the valve head in a retracted open position.

Fig. 2 is a sectional view taken through the valve head, guide and thermostat, and showing the relation of parts assumed when the valve head is in extended or closing po- 75 sition.

Fig. 3 is a vertical sectional view through a modified form of valve casing wherein a valve is provided to prevent back flow of fluid with the radiator.

Referring now more particularly to Figs. 80 1 and 2 of the accompanying drawings, 5 designates the body of the trap which is closed at one end by the end plate 6 and which has an integral closure at its other end provided with the laterally projecting 85 inlet nipple 7 which is adapted to be connected with the bottom portion of the radiator, air inlet nipple 8 for connection with the suitable drain depending from the casing. Threaded in the inlet nipple 7 is 90 a sleeve 9 which is adapted to extend into the casing to form an adjustable seat for the thermostat controlled valve.

This valve comprises a head plate 10 pro- 95 vided with a central boss 11 in which is 95 threadedly engaged one end of the valve stem 12 which extends laterally therefrom and is passed slidably through the closed end of a guide sleeve 13, the other end of this sleeve being open and threadedly engaged 100 in a hollow boss 14 formed on the end plate 6. Threaded on the other end of the stem 11 is a collar 15 which forms a sliding bearing in the sleeve, and disposed between this collar 15 and the closed end of the guide 105 sleeve is an expansile spring 16 which nor- mally holds the valve plate in a retracted position. Formed intermediately on the guide sleeve 12 is a circumscribing flange 17 and this flange in conjunction with the valve 110 head plate serves to hold the thermostat member, which comprises a pair of flexible

plates 18 each provided with an annular series of corrugations in the usual manner. The central portions of the plates are provided with apertures which receive the 5 closed end of the sleeve and the boss of the valve plate respectively and the edges of the valves are engaged in and are soldered in annular grooves 19 formed in the boss and sleeve immediately adjacent to the flange 16, 10 and valve plate respectively, the edges of the plates having a snapping engagement in said grooves. The outer edges of the plates are directed laterally to form flange portions disposed inlapping relation and soldered together. 15

For filling the thermostat member with the desired volatile fluid, the sleeve is provided between the plates with a plurality of apertures 20 and the fluid is poured into the 20 open end of the sleeve and passes through these apertures into the annular chamber formed by the flexible plates. The open end of the sleeve is then closed by the cap member 21 threaded therein and a further cap 25 of solder 22 is disposed over the cap member 21 and the end of the sleeve to procure a hermetic seal.

By the foregoing structure of thermostat member, it is seen that a maximum flexibility is had, particularly over those types of 30 thermostats wherein the flexible plates are held by certain washer members against flexibility throughout.

As the spring 15 performs the function of 35 retracting the valve head, the thermostat plate 17 need not necessarily be of resilient material, and thus a more positive operation is provided for and an economy of structure is also procured. The valve stem is guided 40 by the closed end of the guide sleeve 12 and by the collar 14 which fits the bore of said guide sleeve and thus the valve head is held at all times in proper axial alignment with its seat, this being an important advantage 45 inasmuch as in various conventional types of valves of this general nature, the valve head is carried entirely by one of the thermostat plates and unequal expansion of the plate causes a distortion of the valve head.

50 Under normal conditions, when the valve head is closed, the steam does not surround the thermostat member, as it is held from the valve chamber. This conduces to an exceedingly sensitive operation of the thermostat member which at the same time does not detract from its efficiency, as the escape of any steam into the casing would actuate the thermostat to close the valve, and normally when steam fills the radiator, the thermostat 55 will by indirect heat therefrom be actuated to hold the valve closed.

Under certain conditions, a cooling of the steam in the radiator causes a partial vacuum resulting in a suction through the drain pipe 60 and to provide against this suction it is de-

sirable to place a check valve between the outlet from the radiator and the drain.

Fig. 3 shows an exceedingly simple check valve structure associated with the present main valve, and in this construction the 70 drain pipe nipple designated here at 8^a depends from a chamber 23 formed in the valve casing under the radiator nipple 6 and threaded in the mouth of this chamber is a sleeve 24 carrying within the chamber a 75 pivoted flap valve 25 which closes the sleeve against flow of fluid into the valve casing from the said chamber.

The foregoing arrangement provides for an exceedingly ready assembly of parts, and 80 conduces to a maximum economy of structure.

The present thermostatically controlled valve supplants the simple check valve heretofore employed between the radiator and 85 drain, and removes the objection encountered in such check valves of requiring a considerable head of water in the bottom of the radiator sufficient to operate the valve. A single thermostat valve however, presents 90 the disadvantage of permitting back flow of water into the radiator upon a partial vacuum being produced therein upon shutting off the steam supply and I have found that the best results are procured by combining a check and thermostatically controlled valve in the manner described, it being noticed that in the present structure the check valve is disposed below the port 7 so that a sufficient head of water within 100 the valve casing 5 may be had to operate the check valve 25 without the level of said head of water extending above the bottom of the radiator.

I claim:

1. In a valve of the class described the combination of a casing including a valve seat, a valve head engageable with the seat, a stem rigidly connected with the valve head, a bearing for the intermediate portion 110 of the stem, said bearing being rigid with respect to the casing, an expansible thermostat member between the valve head and bearing for advancing the head, and a spring between the free end of the stem and the 115 bearing for retracting the valve head. 105

2. A thermostat valve head unit comprising a sleeve closed at one end, a valve head, a stem on the head slidably passed through the closed end of the sleeve, a thermostat 120 chamber surrounding the sleeve adjacent the valve and connected with the valve head and sleeve, ports in the sleeve communicating with the chamber, a spring in the sleeve engaging the stem and a closure for the 125 other end of the sleeve.

3. A thermostatically controlled valve head unit comprising a sleeve having one end closed, a valve head, a stem on said head slidable through the closed end of the 130

sleeve and a thermostat chamber between the sleeve and valve head and having its walls connected therewith, ports in the closed end of the sleeve communicating with said 5 chamber and a closure for the other end of the sleeve.

4. A thermostatically controlled valve head unit comprising a sleeve having one end closed, a circumscribing flange formed 10 intermediately on the sleeve, a valve head, a stem on the valve head slidably passed through the closed end of the sleeve, thermostat plates secured to the sleeve and valve head, the edge portions of said plates being directed laterally inlapping relation 15 and secured together to form a chamber port in the closed end of the sleeve communicating with said chamber, and a closure for the other end of the sleeve.

20 5. In a valve structure of the class described the combination of a main valve casing, closed at one end, an inlet port in said end, a thermostatically controlled valve head in the casing for closing the inlet port, 25 a closure for the other end of the casing, a

chamber formed in the first end of the casing below the inlet port, an outlet communicating with the chamber, a sleeve threaded in the chamber, and a flap valve carried by the sleeve and adapted to seat 30 on the end thereof.

6. In a valve of the class described the combination of a valve seat, a valve head engageable with the seat, a thermostat member including relatively movable portions 35 one of which is connected with the valve head, a stem rigidly extending from the head, a member connected with the other thermostat portion and telescopically slidably engaging the stem, and a rigid support 40 for said member.

In testimony that I claim the foregoing I have hereunto set my hand at Milwaukee, in the county of Milwaukee and State of Wisconsin, in the presence of two witnesses. 45

JOHN S. BRENNAN.
